FLUID OPERATED PRESSING MACHINE

Harry D. Forse, Anderson, Ind.

Application December 6, 1937, Serial No. 178,375

4 Claims. (Cl. 38—40)

This invention relates to certain new and useful improvements in fluid operated pressing machines.

In pressing machines of the general type disclosed in this application, it has heretofore been the practice to construct such machines with the power unit thereof permanently built into the machine frame with different elements of the power unit somewhat inaccessible for repair or replacement and when such repairs or replacements are required which is quite frequent due to heavy duty of pressing machines, the latter is placed out of service for a considerable period of time for repair work.

It is therefore the primary object of this invention to construct a fluid operated pressing machine wherein the power unit for controlling the opening and closing movement of the lever head and steam chest carried thereby for cooperation with the buck is mounted within a casing at the front side of the machine frame with the casing easily and quickly removed from the machine frame carrying the power unit therein with a new power unit substituted therefor while the damaged unit is being repaired, a minimum of time being required for removal of the damaged power unit and replacement of a new one.

A further object of the invention is to provide a fluid-operated pressing machine wherein a manually operated handle carried by the lever head is movable independently thereof for the operation of pneumatic devices that in turn effect the opening and closing movements of the lever head and steam chest carried thereby relative to the buck, a link and lever system being interposed between the lever head and fluid operated devices for effecting rapid opening and closing movements of the lever head and also operative after closure of the lever head for imparting increased pressure thereto and corresponding increased pressure of the steam chest on the buck.

The pressures to which a pressing machine of the type disclosed herein is subjected rapidly wears down the padding and a further object of this invention is to provide a padding-wear indicator so that an operator may tell at a glance when repadding of the press is required.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a side elevational view of a fluid operated pressing machine constructed in ac-

cordance with the present invention, the lever head carrying the steam chest being illustrated in its elevated open position;

Figure 2 is a side elevational view, similar to Figure 1, showing the lever head and steam chest carried thereby in closed position relative to the buck;

Figure 3 is an inner face view of the casting that houses the power unit at the front side of the machine removed from the machine and with the power unit removed from the casing;

Figure 4 is a vertical cross-sectional view taken on line 4—4 of Figure 3;

Figure 5 is a fragmentary front elevational view of the machine frame, with the bed, buck and lever head removed and with the front wall of the removable power unit carrying casing removed to illustrate the power unit; and

Figure 6 is a vertical cross-sectional view of the mechanism shown in Figure 5.

Referring more in detail to the accompanying drawings, the fluid operated pressing machine is mounted upon a stand or table of any preferred character common to machines of this general type, the reference character 10 designating in general a frame supporting a table 11 at its upper end through which a standard 12 passes from the frame for the support on the upper end thereof of a buck 13. The rear side of the frame 10 carries an upstanding bracket 14 upon which a lever head 15 is pivotally mounted intermediate its ends, the lever head carrying a steam chest 16 that is adapted to be lowered for engagement with the buck 13 as shown in Figure 2. As shown in Figures 1 and 2, a removable casing 17 for the power unit having a detachable front wall 18 is secured to the front side of the frame 10 by means of a pair of screw bolts 19 shown in Figure 5 that pass through a pair of lateral ears 20 carried by the casing 17 with the two screw bolts 19 constituting the sole means for removably securing the casing 17 to the frame. Lugs 21 depending from the lower end of the casing 17 interfittingly engage an adjacent part of the frame 10 as shown in Figures 5 and 6.

The power unit for the pressing machine is carried by the casing 17 and is bodily removable therewith from the machine frame 10 for purposes of repair or the like and said power unit comprises a cylinder 22 shown more clearly in Figures 5 and 6 as being pivotally suspended at its upper end upon the bolt 23 that in turn is mounted at its opposite ends in bearings 24 depending from the top wall of the casing 17. A fluid or air operated piston within the cylinder 22 is carried by a piston

rod 25 projecting from the lower end of the cylinder 22 for attachment to a part of the operating mechanism for the lever head 15 to be presently described. A bridge plate 26 extends between 5 the side walls of the casing 17 at the outer side thereof and said bridge plate has mounted thereon at the outer side thereof and inwardly of the removable cover wall 18, a valve box 27 carrying a pair of valves 28 and 29 carrying valve stems 30 10 and 31 respectively extending upwardly therefrom and the initial positions of said valves 28 and 29 consists of one valve being open while the other one is closed and to facilitate the description of the operation of the device, the valve 29 will be 15 referred to as the one normally closed while the valve 28 will be the normally open valve. An arm 32 rises from the valve box 27 between the valves 28 and 29 and pivotally supports at the upper end thereof as at 33, the lever 34 that has 20 the end 35 thereof engaged by one end of the coil spring 36 with the other end of said spring anchored as at 37 to the bridge plate 26. As shown in Figure 5, the valve stems 30 and 31 are loosely connected as at 38 to the lever 34 at opposite sides 25 of the pivot 33 to effect operation of the valves 28 and 29, the spring 36 normally holding the valve 28 in open position with the valve 29 in closed position. A pipe 39 arranged at the inner side of the casing 17 inwardly of the bridge plate 26 is attached at its upper end as at 40 to the valve box 27 and the lower end of said pipe 39 has a union connection 41 with a pipe fitting 42 in the machine frame 10 that is in communication with a source of fluid supply. The valves 28 and 29 30 have a flexible pipe connection 43 with the head of the cylinder 22 for the delivery and exhaust of air to and from the cylinder, the valve box 27 also having a muffler outlet or exhaust pipe 44.

As shown more clearly in Figures 1, 2 and 6, 40 a lever 45 is pivotally mounted adjacent one end thereof as at 46 in the lower end of the frame 10 adjacent the rear portion thereof and the forward end of the lever 45 terminating adjacent the front of the frame 10 below the open lower end of the 45 casing 17 has a removable pin connection 47 with the lower end of the piston rod 25. The rear end of the lever 45 that projects outwardly of the rear side of the machine frame 10 has pivotally attached thereto as at 48, the lower end of a 50 toggle link 49 that is pivotally attached at its upper end as at 50 to a second toggle link 51 which in turn is pivoted as at 52 at its other end to the rear end of the lever head 15. When the lever head 15 is in its elevated open position as shown in 55 Figure 1, the toggle levers 49 and 51 are folded or collapsed and said lever head is retained in such position by means of coil springs 53 attached respectively at their ends to opposite sides of the lever head 15 as at 54 rearwardly of the head pivot 50 and to the lower sides of the machine frame as at 55. A cam track 56 is anchored at its ends as at 57 to supports on the machine frame 10 and a roller 58 working in the cam track has pivotally attached thereto one end of an arm 59 that has its 60 other end pivotally attached as at 60 to the toggle link 49 adjacent the lower end thereof, the roller 58 also having pivotally attached thereto one end of an arm 61 that has its other end attached as at 62 to the lever 45 adjacent the front side of 65 the machine frame, this arrangement acting to provide increased pressure in the closing of the steam chest 16 upon the buck 13.

A lever head 15 is fluid or pneumatically operated and to render active the devices for moving 70 the lever head, manually operated means is car-

ried by said lever head, but is not intended for manual operation of the latter either in opening or closing movements of the lever head.

The manually operated devices include an arm 63 that is pivotally mounted on the lever head 15 as at 64, the front end of the arm 63 carrying a downwardly directed guard 65 provided with a handle 66. The rear end of the arm 63 beyond the pivot 64 is pivotally connected as at 67 to one end of a link 68 which in turn is pivotally connected as at 69 to a cam block 70 pivoted on the head 15 as at 71. A toggle arm 72 carried by the arm pivot 64 has one end of a coil spring 73 attached thereto as at 74 while the other end of the spring is attached as at 75 to the lever head 15. A lever comprising portions 76 and 77 is pivoted intermediate its ends as at 78 on the arm 14 rising from the machine frame 10, the upper end of the lever portion 76 being engaged by the cam 70 while the lower portion 77 of said lever is pivotally attached as at 79 to a forwardly directed rod 80 that extends into the upper end of the casing 17 as shown in Figures 1, 2 and 6.

A bell crank lever 81 is pivotally mounted on a pin 82 mounted in the bearing 83 in a side wall 25 of the casing 17 as shown in Figures 3 to 6 and the forward end of the rod 80 is engaged with the upper leg 85 of the bell crank lever 81, while the other lower leg 86 of the bell crank lever is engaged with the lower end of an angle arm 87 that 30 has its upper end attached to the end 88 of the lever 34 for the operation of the valves 28 and 29 as shown in Figure 5.

In pressing machines of the type disclosed herein, the padding is subjected to severe wear and it 35 is the usual practice to repad the steam chest and buck weekly and to enable the operator to determine the amount of wear on the padding, an indicator is provided and is operated by the plunger rod 25 during the lowering movement of 40 the latter. As shown more clearly in Figures 5 and 6, the block 89 mounted within the frame 10 below the open lower end of the casing 17 carries a horizontal pin 90 for the pivotal support of an indicator arm 91 that projects upwardly through 45 a slotted and graduated dial plate 92 carried by the front wall of the frame, the pivot point 93 of the indicator arm 91 being tensioned as at 94 for holding the indicator arm in its shifted position. The lower end 95 of the indicator arm carries a 50 wear plate 96 that is in the path of lowering movement of the piston rod 25 to be engaged by said piston rod as diagrammatically illustrated at 25a in Figure 6.

Assuming the lever head 15 to be in its raised 55 and open position as shown in Figure 1 and it being desired to lower the head and place the chest 16 in contact with the buck 13, the handle 66 is gripped for moving the arm 63 on its pivot 64 and which movement positions the guard 65 slightly 60 below the chest 16 as well as moving the cam 70 through the medium of the link 68 attached to said arm 63 for the operation of the lever elements 76 and 77 to shift the rod 80 for opening the normally closed valve 29 and closing the normally 65 open valve 28 through the medium of the bell crank lever 81 and angle arm 87 extending between said bell crank lever and the lever 34, movement of the lever 34 being accomplished against the tension of the spring 36. When the arm 63 70 is lowered as stated, the spring device 73 holds the same in lowered position by moving to a point below the arm pivot 64 which movement positions the cam 70 for holding the rod 80 in its projected position with the valve 28 open for the supply of 75

fluid under pressure to the cylinder 22. The piston in the cylinder 22 projects the piston rod 25 for the operation of the lever 45, lowering movement of the lever 45 on its pivot 46 moving the 5 roller 58 downwardly through the cam track 56 for shifting the toggle link 49 by means of the arms 61 and 59 carried by said roller 58 and attached respectively to the lever 45 and toggle link 49, the straightening movements of the toggle links 49 10 and 51 effecting upward movement of the rear end of the lever head 15 and downward movement of the forward end thereof for placing the chest 16 in engagement with the buck 13. The upper portion of the cam track 56 effects rapid movement 15 of the connected toggle links 49 and 51 and movement thereafter of the roller 58 in the cam track 56 produces increased pressure of the chest 16 on the buck 13. During the downward projection of the piston rod 25, the lower end thereof moves into engagement with the lower end 95 of the indicator arm 91 for causing the latter to move over the graduated dial plate 92 which indicates the 20 degree of wear of the padding of the machine. A reverse operation of the element is effected when 25 it is desired to elevate the lever head 15 from the closed position shown in Figure 2 to the open position shown in Figure 1, the initial manual operation of the arm 63 acting to relieve pressure of the rod 80 of the bell crank lever 81, the initial 30 manual movements of the arm 63 being retained in its released position by the spring device 73 and at this time the valve 29 is closed and the valve 28 opened by movement of the lever 34 to permit exhaust of air from the cylinder 22 by way of the 35 flexible pipe 43 to the exhaust muffler pipe 44.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:

1. In a fluid operated pressing machine of the character described, a frame, a buck rising therefrom, a lever head carrying a steam chest above the buck, operating levers for the lever head and

steam chest carried by the frame, a removable casing carried by the front side of the frame, a complete power unit for operation of the lever head mounted in the removable casing, the power unit including an air cylinder having connection 5 with the operating levers for the lever head, air control valves for the cylinder and means carried by the frame and head for operation of the air control valves.

2. In a fluid operated pressing machine of the character described, a frame, a buck rising therefrom, a lever head carrying a steam chest above the buck, operating levers for the lever head and steam chest carried by the frame, a removable casing carried by the front side of the frame, a 15 complete power unit for operation of the lever head mounted in the removable casing, the power unit including an air cylinder having connection with the operating levers for the lever head, air control valves for the cylinder and means carried 20 by the frame and head for operation of the air control valves, including a cam movable on the head, a manually movable arm and a guard carried by the head for initial operation thereof and a connected lever and plunger rod operated by the 25 cam with the plunger rod operating the air control valve.

3. In a fluid operated pressing machine of the character described, a frame, a buck rising therefrom, a lever head carrying a steam chest above 30 the buck and a power unit for operation of the head carried by the front of the frame and including a reciprocating rod, and a padding compacting indicator carried by the frame and including a pivoted lever adapted to be operated by said re- 35 ciprocating rod.

4. In a fluid operated pressing machine of the character described, a frame, a buck rising therefrom, a lever head carrying a steam chest above the buck, a power unit for operation of the head 40 carried by the frame and including an air cylinder having a piston therein and a piston rod carried by the piston with the free end thereof projecting outwardly of the cylinder and a padding compacting indicator carried by the frame including 45 a lever disposed in the path of movement of the piston rod for operation thereby.

HARRY D. FORSE.
